PAGE 2

F I G. 2

FIG. 3

FIG. 1 is a front elevational view of an X-ray image intensifier showing our new design, the rear being substantially a mirror image thereof;

FIG. 2 is a left-side elevational view thereof; and

FIG. 3 is a top plan view thereof, the parts shown in broken lines in FIGS. 1 and 2 being omitted for convenience of illustration.

The essential features of this design reside in the portions shown in solid lines of the drawing.

We claim:

The ornamental design for an X-ray image intensifier, substantially as shown and described.
